UNITED STATES PATENT OFFICE.

HARRY P. GRAY, OF OAKLAND, CALIFORNIA, ASSIGNOR TO UNITED ENGINEERING WORKS, OF SAN FRANCISCO, CALIFORNIA, A CORPORATION OF CALIFORNIA.

AIR-SUCTION VALVE.

1,158,679.

Specification of Letters Patent.

Patented Nov. 2, 1915.

Application filed March 8, 1915. Serial No. 12,823.

To all whom it may concern:

Be it known that I, HARRY P. GRAY, a citizen of the United States, residing at Oakland, in the county of Alameda and 5 State of California, have invented new and useful Improvements in Air-Suction Valves, of which the following is a specification.

The present invention relates to air suction valves of internal combustion engines 10 working on the two-stroke principle and using the crank case as an air pump for scavenging the working cylinder.

The object of the invention is to provide a simple and effective non-return valve of 15 cheap construction for admitting air to the crank case.

In the accompanying drawing, Figure 1 is a sectional view of a two-stroke internal combustion engine equipped with my improved air suction valves; Fig. 2 is an enlarged inner side view of one of the valves detached; Figs. 3 and 4 are sectional views on the lines 3—3 and 4—4 respectively of Fig. 2; Fig. 5 is a view similar to Fig. 4 of 25 a modified form of the invention; and Figs. 6, 7, and 8 are views similar to Figs. 2, 3 and 4 respectively of a further modification of the invention.

Referring to the drawing, 1 indicates the 30 crank case of a two-stroke internal combustion engine, to which crank case air is admitted through openings 2 therein. Over each opening is a plate 3 having holes 4 therethrough by which it can be secured to 35 the wall of the crank case and having valve openings 6, which extend parallel with each other in two series, separated from each other by a bar 7 formed integral with the plate. Upon the inner side of said plate 40 over pairs of aligned openings 6 of the two series, are placed spring metal valves 8 closing said openings, and said valves are held in place by a bar 9 immediately over the bar 7 and secured thereto by screws 10 screwed 45 through the bar 9 into the bar 7 between the valve. Each opening 6 tapers slightly towards its inner side or that next the valve. Stop bars 11, secured to the plate 3 over the 50 terminal portions of the valve, limit their outward movement.

The bar 7, and therefore also the bar 9, extends obliquely across the plate, so that the valves of each series are shorter at one end of the series than at the other. It is

found that by such construction the valves 55 open in succession, each valve opening when sufficient suction is exerted thereon, the longer valve being less able to resist the suction thereon than the shorter. On account of their opening in succession they admit air 60 gradually and without any appreciable noise, whereas if the valves were all of equal length, they would all open simultaneously, and the full amount of air would rush in instantaneously with considerable noise. 65

In the modification of the invention shown in Fig. 5, the valves are secured to the plate at one end, as shown at 12.

In the form of the invention illustrated in Figs. 6, 7 and 8, the valve openings 6 are 70 formed in the plate 3 within a circular wall 13, and the bar 7 extends diametrically across said plate, the valve openings extending at right angles to said bar to a point near said circular wall, so that those nearest 75 the center of the bar are the longest and those at the end of the bar are the shortest.

I claim:

1. An air suction valve for internal combustion engines comprising a plate secured 80 to the frame of the engine over an opening therethrough and having a series of openings therein, spring-metal valves of unequal length on the inner side of said plate closing said openings, and means for securing 85 said valves to the plate at one end only of each opening.

2. An air suction valve for internal combustion engines comprising a plate secured to the frame of the engine over an opening 90 therethrough and having a series of openings therein, spring-metal valves on the inner side of said plate closing said openings, and a bar over said valves and secured to said plate. 95

3. An air suction valve for internal combustion engines comprising a plate secured to the frame of the engine over an opening therethrough and having a series of openings therein, spring-metal valves on the inner side of said plate closing said openings, a bar over said valves and screws between the valves and securing the bar to the plate. 100

4. An air suction valve for internal combustion engines comprising a plate secured 105 to the frame of the engine around an opening therethrough and having over said opening spaced parallel bars, the plate being open

between said bars to form parallel openings, and a transverse bar dividing said openings into two series.

5. An air suction valve for internal combustion engines comprising a plate secured to the frame of the engine around an opening therethrough and having over said opening spaced parallel bars, the plate being open between said bars to form parallel 10 openings, and an obliquely extending transverse bar dividing said openings into two

series, the openings of each series gradually increasing in length from one end of the series to the other.

In testimony whereof I have hereunto set 15 my hand in the presence of two subscribing witnesses.

HARRY P. GRAY.
